FLEXIBLE TRANSMISSION COUPLING FOR THREE-WHEELED VEHICLE

James H. Mayland, 173 Southwood Drive,
Old Bridge, N.J. 08857

Filed July 11, 1968, Ser. No. 12,710

Term of patent 14 years

Int. Cl. D12—99

U.S. Cl. D55—1

FIGURE 1 is a front elevational view of a flexible transmission coupling for three-wheeled vehicle showing my new design.

FIGURE 2 is a side elevation as indicated along the line 2—2 of FIGURE 1.

FIGURE 3 is a top view as indicated along the line 3—3 of FIGURE 1.

FIGURE 4 is a bottom view as indicated along the line 4—4 of FIGURE 1.

I claim:

The ornamental design for a flexible transmission coupling for three-wheeled vehicle, substantially as shown and described.
